UNITED STATES PATENT OFFICE.

JOHN HOWARD WAY AND ALBEN WARREN WAY, OF PHILADELPHIA, PENNSYLVANIA, ASSIGNORS TO WAY WORKS, INCORPORATED, OF PHILADELPHIA, PENNSYLVANIA, A CORPORATION OF PENNSYLVANIA.

HINGE.

Application filed May 22, 1924. Serial No. 715,172.

Our invention relates to certain improvements in hinges which are designed particularly for use in connection with the doors of automobiles, and other vehicles.

5 One object of the invention is to design a hinge so as to allow the door to be fitted properly to the door opening.

A further object of the invention is to design a hinge so that the wearing surfaces are 10 not exposed to view and to the weather.

A still further object of the invention is to design a hinge so that the formation of fins during the process of manufacture is prevented.

15 These objects we attain in the following manner, reference being had to the accompanying drawings, in which,

Fig. 1 is a side view of our improved hinge;

20 Fig. 2 is a plan view;

Fig. 3 is a sectional view on the line 3—3, Fig. 1;

Fig. 4 is a transverse sectional view on the line 4—4, Fig. 3;

25 Fig. 5 is a view illustrating our invention as applied to a three knuckle hinge; and

Fig. 6 is a view showing our invention as applied to a hinge having a non-adjustable pintle.

30 A leaf 1 of the hinge has three knuckles 2, 2^a, and 2^b, while a leaf 3 of the hinge has two knuckles 4 and 4^a. This is known as a five knuckle hinge. The leaf 3 has a vertical flange 5, which extends back of the two 35 knuckles and materially strengthens the leaf.

The pintle 6 has a head 7 which is notched at its periphery, as shown, to receive projections that are formed in the walls of a recess

40 8 in the upper knuckle 2. The head is slotted for the reception of a screw driver so that the pintle can be turned, when its head is raised clear of the knuckle, to adjust one leaf in respect to the other. This pintle has

45 a concentric portion 9 of large diameter, and a concentric portion 10 less in diameter than the portion 9. Between these two portions is an eccentric portion 11. The knuckles 4 and 4^a fit the eccentric portion 11, as shown clearly in Fig. 4, while the knuckles 2 and

2^b fit the concentric portions 9 and 10. The intermediate knuckle 2^a has an opening of a diameter the same as the knuckle 2, which allows the eccentric 11 to turn freely therein when the pintle is turned to adjust one leaf 55 of the hinge in respect to the other. The lower end of the pintle is enlarged and split, as shown in 12, to hold the pintle frictionally in position.

It will be noticed that the meeting surfaces 60 of the several knuckles are beveled. The knuckles 2, 2^a and 2^b are beveled at 13, while the knuckles 4 and 4^a are beveled at 14, so that the contacting surfaces between the two sets of knuckles are less in diameter than the 65 knuckles. By this construction, the exposed beveled surfaces can be painted, or enameled, while the surfaces will be protected from the weather and from sight, making a very neat appearing hinge. 70

During the process of manufacture, the spaces between the knuckles are milled and by beveling the surfaces as indicated at 13 and 14, fins, which are usually formed during this process, are not formed, owing to the 75 fact that there are no sharp angles.

In Fig. 5 is illustrated a three knuckle hinge in which the central knuckle 2^a is omitted, and the knuckle 4^b of the other leaf extends the full distance between the two 80 knuckles 2 and 2^b.

In Fig. 6, the invention is shown as applied to a hinge, in which a pintle 6^a is of an even diameter. This is not an adjustable hinge. The knuckles 2^c have openings of the 85 same diameter as the knuckles 4^c. The pintle 6^a may be prevented from turning in the knuckle 2^c by the head shown, or may be a loose pintle, if desired.

It will be understood that hinges of automobiles should be so designed that the wearing surfaces will not be exposed, which allows rust to form, as these hinges become unsightly and detract from the general appearance of the automobile. By making the 95 hinge in the manner shown and described, a neat hinge is produced, the wearing surfaces of which are not exposed, and which can be readily adjusted to fit the door to the door opening. 100

We claim:

The combination of a wrought-metal hinge having two leaves, each leaf having a series of knuckles; pintle openings in the knuckles, the opposing faces of the knuckles being beveled to reduce the area of the wearing surface; and a pintle extending through the

knuckles and having an eccentric portion by which one leaf is adjusted with respect to the other, the slots between the knuckles ¹⁰ formed by the beveled portion being deep and narrow.

JOHN HOWARD WAY.
ALBEN WARREN WAY.
